UNITED STATES PATENT OFFICE.

FREDERICK A. WARD, OF DETROIT, MICHIGAN, ASSIGNOR TO THE GEAR GRINDING MACHINE COMPANY, OF DETROIT, MICHIGAN, A CORPORATION OF MICHIGAN.

GRINDING-WHEEL-TRIMMING MECHANISM.

1,133,075.

Specification of Letters Patent. Patented Mar. 23, 1915.

Application filed January 20, 1909. Serial No. 473,251.

To all whom it may concern:

Be it known that I, FREDERICK A. WARD, a citizen of the United States, and a resident of Detroit, in the county of Wayne and State of Michigan, have invented a certain new and useful Grinding-Wheel Trimming Mechanism; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to mechanism for truing the operating surfaces of grinding-wheels or the like to maintain such surfaces uniform for successive operations, and has particular reference to improvements on the mechanism shown and described in the United States Letters Patent No. 888,675, granted jointly to William N. Taylor and myself on May 26, 1908.

An object of my invention is the provision in a machine of this class of simple and efficient means for automatically controlling the movements of the wheel-trimming members to cause the working surfaces of the wheel to be shaped to suit the surface to be ground, which means is capable of being removed to permit the substitution therefor of similar means of different shape whereby the machine may be easily and quickly changed to maintain the working surface of a grinding-wheel in any predetermined form as the shape or size of the surfaces to be ground may require.

A further object of my invention is to improve upon the construction and arrangement of the parts of the mechanism described in said Letters Patent No. 888,675, whereby to increase the working efficiency, practicability, and commercial value of the machine, as will hereinafter be more fully explained.

The invention is fully described in the following specification, and while in its broader aspect it may be embodied in different forms of machines and its parts differently arranged and constructed, a preferred form is shown in the accompanying drawings, in which,—

Figure 1 is a side elevation of a machine embodying the invention. Fig. 2 is an en-

larged side elevation of the trimming mechanism and associated parts, with the rear trimmer members in elevated position and with portions of the frame in section. Fig. 3 is an enlarged front elevation of such mechanism with portions of the frame in section. Fig. 4 is an enlarged plan view thereof with a portion of the frame or housing in horizontal section, and Figs. 5, 6 and 7 are enlarged rear, plan and side views of portions of the mechanism employed for trimming the side surfaces of the grinding-wheel.

Referring to the drawings, 1 designates the frame, which is provided at one end with the elevated portion 2 carrying the grinding parts, and at the other end with the elevated portion 3 carrying the work-mandrel and controlling parts. The frame part 2 is formed on its top with a slide-way on which a carriage 4, carrying the grinding-wheel 5 at its forward end, is slidingly mounted to enable such wheel to have movements transversely of the gear or other work 6 to be ground, as is fully described in said Patent No. 888,675. As the mechanism employed for lowering the grinding-wheel 5 after each grinding operation to compensate for wear and for the material removed from its working surface by the trimming process forms no part of the present invention, reference is made to said former Letters Patent for a description of the same.

The carriage 4 has its reciprocatory movements actuated by the rotation of a cam-drum 7, which is mounted on a shaft 8 within the portion 2 of the frame, and has its periphery provided with a cam-groove 9 in which operates a roller 10 carried by a stud projecting downwardly from the carriage 4. Rotation is communicated to the shaft 8 in any suitable manner.

Supported by the frame 1 in advance of the elevated portion 2 and beneath the grinding-wheel 5 when in retracted position, as shown in the drawings, is a frame part 11, which carries the trimmer mechanisms. Rising from the rear of this frame part is the rear trimmer-head supporting-standard 12, on the top of which are mounted the two transversely adjustable blocks 13, 13, which preferably have their bottoms grooved to work over a tongue or rib formed on the standard top, as shown in Fig. 2, and are

secured in adjusted position by means of screws 14, 14, which have their shanks projected through slots therein and threaded into the standard. To further insure the 5 blocks against relative contracting movements when set in adjusted position, a spacing pin 15 is inserted in a socket (not shown) in the standard top with its head disposed between and abutting against the 10 inner ends of such blocks. A plurality of these pins having their heads of varying thicknesses may be provided to adapt them to be used to hold the blocks in various positions of relative adjustment.

15 Mounted on a stud 17 projecting forwardly from each block 13 is one of a set of vertically-disposed levers 18, 18, each of which has its upper end disposed contiguous to a lower side edge of the grinding- 20 wheel and enlarged longitudinally of the plane of movement of such wheel to form a bearing-head 19, in which a short shaft 20 is mounted, as shown. Each of the shafts 20 has its forward end preferably enlarged, 25 as shown, and provided with a transverse opening in which a trimmer-finger 21 is mounted for longitudinal adjustment and secured in adjusted position by a set-screw 22. Arms 23, 23 project downwardly and 30 inwardly from the rear ends of the shafts 20, 20 and are provided at their free ends with laterally-projecting studs 24, 24, which work in a slot 25 provided transversely in the upper end of the vertical push-rod 26, 35 see Figs. 5, 6 and 7, thus adapting a vertical movement of such rod to effect a rocking of the arms 23, 23, shafts 20, 20 and trimmer-fingers 21, 21.

The push-rod 26 projects downwardly 40 through the standard 12 and top of the frame part 11 and is yieldingly held in lowered position by a coiled expansion-spring 27, which encircles it within said standard and has opposite ends thrust against the under- 45 side of the standard top and a pin 28 carried by the rod, as shown in Figs. 1 and 2. The rod 26 is raised against the tension of the spring 27 by the rocking of an arm 29, which projects horizontally from a rock- 50 shaft 30 and has its free end forked to work over a pin 31 at the lower end of the rod. The shaft 30 is journaled transversely of the machine in suitable bearings provided in the frame part 2, as shown in Fig. 4, and 55 carries a downwardly-projecting arm 32 at its outer end, the lower end of which is forked to engage over a pin 33 projecting laterally from a horizontal push-bar 34, which is mounted in bearings 35 at one side 60 of the machine, as shown in Figs. 1 and 2. The forward movements of the push-bar 34 are caused by the forward rocking movements of a rocker-arm 36, which is carried at one end of a rock-shaft 37 with its upper 65 or free end in position to have contact with

the rear side of a roller or projection 38 on the side of such bar. The shaft 37 is journaled in the frame 1 transversely thereof and beneath the forward end of the drum 7, and carries an arm 39 which projects upwardly 70 in the path of forward movement of a pin 40 on the sleeve 41. This sleeve is carried by a shaft 42, mounted longitudinally of the frame beneath the drum 7, and has movements imparted thereto longitudinally of the 75 shaft 42 due to a roller 43 on its top working in the cam-groove 9 of the drum, as shown in Fig. 2.

In order to cause the trimmer ends of the trimmer-fingers 21, 21 to describe irregular curves or lines of predetermined shape when such fingers are rocked by oscillations of their respective carrying-shafts 20, 20, the levers 18, 18 carry at their lower ends inwardly-projecting pins 44, 44 which abut 80 at their inner ends against the opposite sides of a form or templet 45, which is mounted on a spindle projecting upwardly from the upper end of a vertically-movable push-rod 46, said pins being yieldingly held 85 in contact with the templet surface by the action of a contraction-spring 47 on said lever. It is thus evident that a vertical movement of the templet 45 relative to the levers 18 simultaneous with a rocking of 90 shafts 20, 20 will impart opposed oscillatory movements to such levers and effect irregular movements of the trimmer ends of the 95 fingers 21, 21 relative to the grinding-wheel while such finger-ends are moving in the 100 arcs of circles concentric to their respective axes, thus causing the templet and levers to coöperate with the shafts 20, 20 and their 105 operating mechanism to communicate the requisite compound oscillatory movements 110 to the trimmer-fingers to shape the operating surfaces of the grinding-wheel to suit the work operated on. A templet 45 may be retained on its carrying spindle by threading 115 a nut 16 to the upper end of such spindle, thus enabling a templet to be easily removed and one of proper shape to suit the 120 contour or size of the work to be operated on substituted therefor.

The templet-rod or holder 46 is mounted 115 for vertical reciprocatory movements in a bearing 48 formed through the top of the frame part 11, and has its lower end forked 120 and carrying a pin 49 with which the forked end of a rocker-arm 50 engages, as shown in 125 Figs. 1, 2 and 3. The arm 50 is shown as projecting rearwardly from a shaft 51, which is mounted transversely of the frame 11 in suitable bearings provided therefor, and carries a vertically projecting arm 52 130 at one end. The forward end of the push-bar 34 is intended to coact with an anti-friction roller 53 carried by the arm 52 to effect a forward oscillation of such arm and a consequent rocking of the shaft 51 to raise 135

the free end of the arm 50 and templet-rod 46 when such push-bar is moved forward as hereinbefore described. A contraction-spring 54 yieldingly acts on an arm 55 projecting upwardly from the shaft 51 and on a pin 56 (Figs. 3 and 4) projecting inwardly from a side of the frame part 11 to normally maintain the shaft 51 and its arms and the push-bar 34 in the position shown in Fig. 1.

5 Rising from the top of the frame part 11 at one side thereof and in advance of the rear trimmer mechanism is a standard 57 having the head 58. Mounted within this head for horizontal movements transversely 10 of the machine is a bar 59, one end of which projects from such head in contiguous position to the lower edge of the grinding-wheel 5 and is vertically apertured to receive the trimmer-finger 60, which is adjustably held therein by means of the nuts 61. This finger carries a diamond or other suitable trimming substance at its upper end, as do also the trimmer-fingers 21, 21, and is preferably adjusted relative to its carrying bar to cause it, when moved transversely of the wheel 5 in engagement with its peripheral edge, to trim such edge. A vertical push-rod 62 is mounted in the standard 15 57 and has its upper end narrowed to work through a slot 63 (Fig. 4) in the bar 59 and tapered, as shown by dotted lines in Fig. 3, to coat with a roller 64 disposed within said slot whereby an upward movement of such rod will impart a trimming 20 movement to the bar 59 and its attached trimmer-finger 60. A coiled compression-spring 65 is mounted in a socket 66 provided in the head 58 at one side of the bar 59 and acts against the inner end of the socket and 25 a thrust-pin 67, which latter projects within the open end of such socket and is attached to the bar 59, whereby to effect a retraction 30 of the bar 59 to its normal position on a lowering of the push-rod 62.

35 45 The raising movements of the push-rod 62 are intermittently caused by a rocking of the rocker-arm 68, which has its free end in forked engagement with a pin 69 at the lower end of such rod and is carried by a 50 rock-shaft 70, see Figs. 2 and 3. This shaft is mounted in suitable bearings longitudinally of the frame and carries an arm 71 at its rear end, which is rocked at a predetermined point in each revolution of the 55 drum 7 by contact therewith of a stud 72, which projects from the forward end of said drum, as shown in Figs. 2, 3 and 4. The engagement of the stud 72 and arm 71 is so timed that the rocking of the shaft 70 60 and consequent raising of the push-rod 62 and trimming movement of the trimmer finger 60 takes place when the vertical center of the wheel 5 in its forward movement stands approximately in transverse alignment with the trimmer-finger 60.

73 designates an arm which is carried by the rock-shaft 30 and is connected by a rod 74 to the mechanism controlling the movements of the work, whereby such mechanism at each rocking movement of said arm 70 is actuated to move the work for successive operations, as is fully described in said former Letters Patent No. 888,675.

75 The operation of my improved machine is as follows:—The drum 7 being set in motion the grinding-wheel 5 is moved forwardly across the work and then returned to the position shown in the drawings due to the roller 10 and its carriage 4 working in the cam-groove 9 of the drum, which 80 groove is suitably fashioned for such purpose, and at a point in the returning movement of the wheel it is lowered a predetermined distance, by mechanism not described herein, to compensate for wear and for the 85 material removed therefrom in the trimming process. When the sleeve 41, which is also reciprocated by the drum 7, is near the limit of its forward movement the grinding-wheel carriage has reached its limit of rearward movement and pauses, due to the 90 roller 10 working in a neutral zone of the groove at such point, until the sleeve 41 completes its forward movement. During this pause of the grinding-wheel and the 95 continued forward movement of the sleeve 41, the pin 40 thereon engages and effects a rocking of the arm 39, shaft 37, and attached arm 36, thus effecting a forward movement of the push-bar 34. As the push-bar 100 100 moves forward it effects a simultaneous rocking of the rock-shafts 30 and 51 through the medium of the respective arms 32 and 52 with which it contacts and a consequent raising of the two push-rods 26 and 46, which attach at their lower ends to the horizontally projecting arms 29 and 50 of such shafts. The upward movement of the push-rod 26 rocks the shafts 20, 20 in unison through the medium of the arms 23, 105 110 23 with which it connects, and effects a consequent oscillation of the trimmer ends of the fingers 21, 21 in the arcs of circles concentric to the axes of their respective shafts. As the fingers 21, 21 are oscillated their 115 trimmer ends are caused to have a movement other than the arc of a circle relative to the grinding-wheel rim, whereby to trim the opposing operating surfaces *a a* of the wheel in predetermined forms, due to the 120 oscillatory movements imparted to the levers 18, 18 carrying the finger-shafts by reason of the movement imparted to the templet or form 45 with which the lower ends of such levers have contact. It is thus apparent that the working surface of the 125 grinding-wheel may be trimmed in any desired form to suit the shape of the surfaces operated on by simply placing a templet of the required shape on the spindle of the 130

push-rod 46. The side surfaces *a a* having been trimmed the cam-groove of the drum acts on the carriage-roller 10 to move the carriage and grinding-wheel forward to operate on the work. When the wheel has reached a point in its forward movement in which its axis stands approximately in a transverse vertical plane with the front trimmer finger 60, the stud 72 on the edge 10 of the drum 7 moves in contact with and rocks the arm 71 on the rock-shaft 70, thus effecting an upward movement of the push-rod 62, and a consequent horizontal movement of the trimmer finger 60 across the lower peripheral edge of the wheel in contact therewith to trim such edge, due to the upper beveled end of the rod 62 coating with the roller 64 which is mounted in the finger-carrying bar 59. When the rod 62 is again lowered the bar 59 is retracted to its normal position by the action thereon of the compression-spring 65. In adapting the machine for operating on work of different shape or size from that previously operated on, a grinding-wheel of the requisite shape is placed on the carriage 4 and the blocks 13, 13 carrying the levers 18, 18 are suitably adjusted on the standard 12 and secured in adjusted position by a tightening of the screws 14, 14 and inserting a spacing pin 15 between their contiguous ends, which pin has its head of proper size to rigidly space the blocks apart. This being done, a templet of the desired form is placed on the push-rod 46, and the machine is then ready for operating.

I desire it to be understood that my invention is not limited to any specific form or arrangement of parts except in so far as such limitations are specified in the claims.

Having thus described my invention, what I claim as new and desire to secure by Letters Patent, is,—

1. In a machine of the class described, the combination of a grinding-wheel, a trimmer part capable of compound oscillatory movements relative to such wheel, and mechanism for imparting compound oscillatory trimming movements to such trimmer part.

2. In a machine of the class described, the combination of a grinding-wheel, a plurality of wheel trimming parts capable of compound oscillatory movements relative thereto, and mechanism for imparting compound oscillatory trimming movements to such parts.

3. In a machine of the class described, the combination of a grinding-wheel, wheel trimming means having trimmer parts capable of like compound oscillatory trimming movements in unison and mechanism for intermittently causing such movements of said parts.

4. In a machine of the class described, the combination of a grinding-wheel, an oscil-

latory part movable to radially trim a side edge of the wheel, and mechanism for imparting oscillatory movements to said part and lateral movements to its axis whereby to cause said part to have irregular trimming movements and means for causing the irregular movements of such part.

5. The combination with a grinding-wheel, of an oscillatory member, a wheel-trimming part carried by said member and capable of oscillation relative thereto, means for oscillating the trimmer part relative to said member, and means for oscillating said member when the trimmer part is oscillated relative thereto.

6. The combination with a grinding-wheel, of a set of oscillatory members, a wheel-trimming part carried by each of such members and capable of oscillation relative thereto, means for oscillating the trimmer parts relative to said members, and means for oscillating said members when the trimmer parts are oscillated relative thereto.

7. The combination with a grinding-wheel, of an oscillatory member, an oscillatory wheel-trimming part carried by said member with its axis parallel thereto and capable of trimming movements relative to such member and mechanism operative to impart relative simultaneous movements to said member and part.

8. The combination with a grinding-wheel, of a set of movable members, wheel-trimming means carried by said members for trimming movements relative thereto, and mechanism operative to impart simultaneous trimming movements to said means relative to said members and simultaneous movements to said members.

9. The combination with a grinding-wheel, of a set of movable members, wheel-trimming means carried by said members and capable of trimming movements relative thereto, the axes of said members and means being parallel, and mechanism automatically operative to intermittently impart trimming movements to said means relative to said members and simultaneous movements to said members.

10. The combination with a grinding-medium, of a lever, trimming means journaled in said lever, means for oscillating said trimming means relative to the lever, and means for moving the lever when the trimming means is oscillated relative thereto.

11. The combination with a grinding-wheel, of a set of levers, a templet associated with such levers to control their movements, trimmer means carried by said levers for operating on opposed portions of the wheel, and mechanism for imparting trimming movements to said means relative to the levers and movement to the templet whereby

the trimmer means have irregular movements.

12. The combination with a grinding-wheel, of a set of movable members, rock-shafts carried by said members, wheel-trimming means carried by such shafts and adapted to operate on opposed surfaces of the wheel, a templet carrying part, a templet removably carried by such part and co-acting with said members, and mechanism intermittently operative to rock said shafts and simultaneously move the templet carrying part and templet to move said members.

13. The combination with a grinding-wheel, of separate trimming means for successively acting on the wheel to trim its operative portion, and mechanism operative to impart compound oscillatory movements to one of said means and reciprocatory movements to the other of said means.

14. The combination with the grinding-wheel, of a horizontally movable member, trimming means carried by said member, means movable to effect a movement of said member and a consequent movement of the trimmer means across the periphery of the wheel and means for automatically imparting intermittent movements to said second mentioned means.

15. The combination with a grinding-

wheel, of a horizontally movable bar, a trimmer part carried by said bar and movable across the periphery of the wheel by a movement of such bar, mechanism for automatically imparting intermittent trimming movements to said bar and trimmer part, and means for retracting the bar after said part acts on the wheel.

16. The combination with a grinding-wheel, of a movable member, a trimmer part adjustably carried by said member and movable thereby across the periphery of the wheel, and means for automatically moving said member to communicate a trimming movement to the trimmer part.

17. The combination with a grinding-wheel, of a reciprocatory member, a trimmer part adjustably carried by said member, and mechanism for automatically actuating said member to intermittently move the trimmer part transversely of the wheel periphery to trim the same.

In testimony whereof I have hereunto signed my name to this specification in the presence of two subscribing witnesses:

FREDERICK A. WARD.
